UNITED STATES PATENT OFFICE

JOHN WARREN VEDDER, OF WORCESTER, MASSACHUSETTS

SUCTION BOX OSCILLATING MEANS

Application filed March 16, 1931. Serial No. 523,008.

This invention relates to a device for oscillating suction boxes on a Fourdrinier paper machine.

The principal objects of the invention are 5 to provide simple and direct means for oscillating the suction boxes so as to prevent the wearing of grooves in the suction box covers and injury to the wire; to provide a drive for the same so connected and arranged 10 that when the Fourdrinier wire stops the oscillation of the suction boxes will stop also, whereby the possible damage caused by the oscillation of the suction boxes when the wire is not operating will be avoided, and to provide 15 an improved support for the suction boxes to enable them to be oscillated in one direction at one end and the other at the other end.

Other objects and advantages of the invention will appear hereinafter.

Reference is to be had to the accompanying drawings, in which

Fig. 1 is a side view of a section of the Fourdrinier part of a paper machine, showing a 25 preferred embodiment of this invention;

Fig. 2 is a plan of the same;

Fig. 3 is a sectional view of the suction boxes, supporting means at one end and the means for operating it;

Fig. 4 is a sectional view on the line 4—4 of Fig. 3;

Fig. 5 is a sectional view like Fig. 3 showing the second eccentric and with the shaft in the same position as in Fig. 3;

Fig. 6 is a plan on reduced scale showing in dotted and full lines the extent and direction of the vibration;

Fig. 7 is a plan of a portion of the machine showing another way of operating it, and

Fig. 8 is a plan of a modification.

The oscillation or vibration of the suction boxes of a Fourdrinier paper machine has taken place heretofore by means of comparatively expensive mechanism to build and also to maintain. It has usually been constructed so that the suction box moves as a whole one way or another. According to this invention the suction boxes are vibrated 50 by moving one end in one direction and the

other in the opposite direction at the same time.

The invention is shown as applied to an ordinary Fourdrinier machine in which the Fourdrinier wire 10 passes over a lower couch 51 roll 11 at one end and another roll at the other end for supporting the wire. The shaft 12 of the lower couch roll is positively driven. On this shaft is a pinion 13 which, by a chain 14, drives a gear 15 and other gearing drives 60 a shaft 16 therefrom, extending transversely across the machine at the end.

On the shaft 16 are two eccentrics 17 and 18. These eccentrics are set oppositely as shown in Figs. 3 and 5 and are connected 65 with blocks 19 which are mounted to slide vertically in a pair of frames 20 which are attached by means of brackets 21 to a pair of supports 22 which carry suction boxes 23 beneath them. The suction boxes are secured 70 to these supports by bolts 24, which are secured to the supports 22 and the suction boxes 23 to hold them rigidly at the two ends. The supports 22 are carried by springs 26 to allow these supports to move longitudinally 75 and sideways. The eccentrics being set oppositely, it will be seen that the motion of the suction boxes indicated in Fig. 6 will take place. One end will move forward while the other end is moving back and they may move 80 sideways slightly.

The parts are rigidly connected but on account of the fact that the maximum motion is only about $1\frac{1}{4}$ " while the length of the suction boxes is approximately the width 85 of the Fourdrinier wire, (that is, from 100" to 200"), the springs 26 are capable of twisting a slight amount so that they accommodate any twist from the motion if necessary.

The result of this is that the suction boxes 90 are moved so that the wire will not wear grooves in their covers as is the case with stationary suction boxes. Another advantage of the construction described is that when the Fourdrinier wire stops the vibration of the 95 suction boxes also stops, thus preventing the suction boxes from moving after the wire has come to rest with the resultant damage possible.

In the form shown in Fig. 7 the shaft 16 100

is operated directly by a motor 27 through a reducer 28. In this case one advantage of the other construction is lost, because the suction boxes can operate when the Fourdrinier wire is stopped and the attendant has to stop the motor 27 at the proper time.

10 In the form shown in Fig. 8 the shaft 36 is provided with two pairs of cams 37, 38 and 47, 48. The two cams 37 and 38 are connected with a pair of supports 32 while the two cams 47 and 48 are connected with a pair of supports 42. In each case each pair of supports carries alternate suction boxes 33 and 43. The cams 37 and 38 are set opposite each other and also the cams 37 and 47. The result is that shown in Fig. 8. The boxes are shifted oppositely at adjacent ends, thus preventing any tendency of the wire being caused to run off to one side.

20 Although I have illustrated and described only three forms of the invention I am aware of the fact that other modifications can be made therein by any person skilled in the art without departing from the scope of the invention as expressed in the claims. Therefore, I do not wish to be limited in this respect but what I do claim is:—

30 1. In a paper machine, the combination with a Fourdrinier wire, and means for operating it, of a pair of supports, a set of suction boxes rigidly carried by said supports and means for reciprocating said supports in opposite directions transverse to the length of the suction boxes at their ends.

2. In a paper machine, the combination with a Fourdrinier wire, a set of suction boxes over which the wire passes, a pair of supports for the suction boxes located at opposite ends, means for rigidly securing the suction boxes to the supports to depend therefrom, a shaft at the end of the series of suction boxes located parallel to their length, a pair of eccentrics on said shaft, set oppositely, and means for transmitting the motion of 45 said eccentrics in a horizontal plane to said supports to move them transversely to the length of the suction boxes.

3. In a paper machine, the combination of a Fourdrinier wire, a set of suction boxes over which the wire passes, a pair of longitudinal supports on the opposite ends of said suction boxes to which the boxes are rigidly secured, yielding means for carrying said supports to permit of motion, a shaft at the 50 end of the series of the suction boxes extending transversely, a pair of eccentrics on said shafts, set opposite each other, blocks in which said eccentrics operate, frames having vertical ways for said blocks, and means for connecting said frames individually with the supports to vibrate said suction boxes in opposite directions at their opposite ends.

4. In a paper machine, the combination with the suction boxes, of means for angularly shifting them so that each two adjacent

boxes move in opposite directions at the same end.

5. In a paper machine, the combination with a set of suction boxes, of two pairs of supports therefor, each alternate box being carried by one pair of supports, and means for vibrating each pair of supports in opposite directions so as to move adjacent ends of the boxes in opposite directions and for vibrating the two supports of each pair in opposite directions. 70 75

6. In a Fourdrinier paper machine, the combination of a set of suction boxes over which the Fourdrinier wire passes, springs for supporting said boxes located near the four corners of the whole set of boxes, and means for simultaneously vibrating the two sides of the set of boxes in opposite directions longitudinally. 80

7. In a paper machine, the combination of the Fourdrinier wire and a set of suction boxes thereunder, with four vertical flat parallel springs for yieldingly supporting the boxes, said springs being capable of twisting, and means for vibrating the two sides of the set of boxes in different directions longitudinally. 85 90

8. In a paper machine, the combination of the Fourdrinier wire and a set of suction boxes thereunder, with springs for yieldingly supporting the boxes, said springs being capable of twisting, and means for moving the set of boxes in such a way as to twist the springs. 95

9. In testimony whereof I have hereunto affixed my signature.

JOHN WARREN VEDDER.
